(57) **CLAIM**

The ornamental design for an espresso coffee machine as shown and described.

DESCRIPTION

1. Espresso coffee machine

1.1 : Perspective

1.2 : Front

1.3 : Back

1.4 : Left

1.5 : Right

1.6 : Top

1.7 : Bottom

Use: the design is incorporated in a coffee machine, in particular, an espresso coffee machine; innovative portion: the innovation points of the design are in the shape of the coffee machine as illustrated in the drawings; figure that shows the design most sufficiently: perspective view (fig. 1.1); the broken lines illustrate portions of the espresso coffee machine excluded from protection and not part of the claimed design.

1 Claim, 7 Drawing Sheets
